UNITED STATES PATENT OFFICE

143,454

DESIGN FOR A NESTED TABLE UNIT

Paul White, Pomona, N. Y.

Application April 27, 1945, Serial No. 119,271

Term of patent 7 years

(Cl. D33—14)

To all whom it may concern:

Be it known that I, Paul White, a citizen of the United States of America, residing in the city of Pomona, county of Rockland, and State of New York, have invented a new, original, and ornamental Design for a Nested Table Unit, of which the following is a specification, reference being had to the accompanying drawing, forming a part thereof.

Figure 1 is a view in perspective of a nested table unit showing my new design. In this figure

one of the table units is shown in an extended position thereof.

Figure 2 is a vertical sectional view of the nested table unit shown in Figure 1, in Figure 2 the extended table unit of Figure 1 being in the nested or closed position thereof.

I claim:

The ornamental design for a nested table unit, as shown.

PAUL WHITE,
